UNITED STATES PATENT OFFICE.

ANGELO PERRI, OF WATERTOWN, MASSACHUSETTS, ASSIGNOR TO REECE SHOE MACHINERY COMPANY, OF BOSTON, MASSACHUSETTS, A CORPORATION OF MAINE.

LASTING MACHINE.

1,420,572.

Specification of Letters Patent. Patented June 20, 1922.

Application filed August 14, 1919. Serial No. 317,498.

To all whom it may concern:

Be it known that I, ANGELO PERRI, a citizen of the United States, residing at Watertown, in the county of Middlesex and 5 State of Massachusetts, have invented a new and useful Lasting Machine, of which the following is a specification, reference being had therein to the accompanying drawing.

This invention is a novel shoe lasting machine. By lasting is understood either or 10 both of the following steps, namely, pulling over the soft leather of the shoe upper at the front and sides near the toe, to conform with the last, and wiping or smoothing the 15 margins of the upper about the last at the toe end, and usually at the heel end also. The present machine may be compared with my prior Patent No. 1,260,084, patented March 19, 1918, and is of the same class, 20 embodying pulling-over mechanism, toe wiping mechanism and heel wiping mechanism, also a shoe holding device or jack shiftable to change the shoe position after the pulling-over, so as to co-operate advantageously with 25 the wiping mechanism. Herein I use the word "position" in the same sense as in the prior patent, namely, to refer either to the posture of the shoe or its location.

The main object of the present invention 30 is to afford a machine and mechanism for performing the lasting operations upon a shoe in a more efficient and more convenient manner and with better results in the product. Specifically it is an object hereof to 35 improve as a whole the class of machine illustrated in said prior patent, including the shiftable jack and the relation of the same to the pulling-over and wiping mechanisms. A further object is to improve the 40 pulling-over mechanism per se, the same having utility irrespective of the jack and wiping mechanisms. Other and more particular objects and advantages of the present invention will be made clear in the hereinafter 45 following description of an embodiment thereof or will be apparent to those skilled in the art.

To the attainment of the objects mentioned, the present invention consists in the 50 novel machine, mechanisms, combinations, devices and arrangements herein illustrated, described or claimed. For convenience the shoe will be designated in the drawings by

the letter S, and when there is a distinction between right and left shoes, the same will 55 be designated S^r, S^l, respectively; the upper by the letter U and the wooden last by the letter L.

The principles, structure and details of the toe wiping mechanism herein indicated 60 are not herein made the subject of claim of invention, and the same may be said of the heel wiping mechanism herein shown; these matters for convenience being made the subject of co-pending applications, showing and 65 claiming the principles, structure and details more fully.

In the accompanying drawings, Fig. 1 is a front elevation of a lasting machine embodying the present invention. 70

Fig. 2 is a vertical section of certain details of the main pedal connections.

Fig. 3 is a left side elevation of the machine shown in Fig. 1, the heel wiping mechanism, which is behind the toe wiping mechanism, being omitted. 75

In Figs. 1 and 3 the parts are shown in their position after a right shoe S^r has been pulled over and engaged by the shifting jack, but before the release of the shoe from the 80 pulling-over mechanism and its shifting into wiping position.

Fig. 4 on a larger scale shows the pulling-over mechanism in the same view as in Fig. 3, working on a right shoe. 85

Figs. 5 and 6 are details taken respectively on the sections 5—5 and 6—6 of Fig. 4.

Fig. 7 is a front elevation of the pulling-over mechanism shown in Fig. 4.

Fig. 8 is a similar view showing the parts 90 reversed for a left shoe.

Fig. 9 is a partial front elevation or skeleton view of the pulling-over levers and their connections.

Fig. 10 is a top view of the puller reversing cam and trip. 95

Fig. 11 is a plan view of the left side gripper of the pulling mechanism.

Fig. 12 is a left elevation thereof.

Fig. 13 is a detached front elevation of the 100 two side grippers.

Figs. 14 and 15 are sections on the lines 14 and 15 of Fig. 12.

Fig. 16 is a front elevation of certain details of the puller reversing mechanism. 105

The remaining figures have more particu-

larly to do with the shiftable jack by which the pulled-over shoe is shifted to wiping position.

Fig. 17 is a front elevation embodying parts of Fig. 1, but omitting the pulling-over mechanism and showing the jack and shoe shifted from pulling-over position to a second or intermediate position, as is preferred, although the shifting might be arranged to pass directly to the third position by a compound movement.

Fig. 18 is a view similar to Fig. 17, showing the jack and shoe shifted to the final or wiping position in relation to the toe 15 wiping at the left and heel wiping mechanism at the right.

Fig. 19 is an enlarged front elevation of a portion of the jack illustrating particularly the shoe holding clamp. This shows 20 the jack in the same intermediate position as in Fig. 17.

Fig. 20 is a right elevation of the mechanism shown in Fig. 19.

Fig. 21 is a plan view of certain details, 25 partly in section on the plane 21-21 of Fig. 20.

Fig. 22 is a view of the same parts shown in Figs. 19 and 20, in right elevation, partly in central section on the plane 22-22 of 30 Fig. 19.

Fig. 23 is a front view, partly in elevation and partly in section on the plane 23-23 of Fig. 20.

Fig. 24 is a front elevation of a detail, 35 namely, the toe clamping pad shown in Figs. 19, 20 and 22.

Fig. 25 is a front view of a modification of the device 253 shown in Figs. 19, etc.

The several component mechanisms which 40 together make up the complete machine are shown in a general way in their co-operative relations in Figs. 1, 3, 17 and 18. The relative arrangements of the several mechanisms will first be described, and subsequently the structure and operation of the 45 respective mechanisms. The machine and its operation are such that the operator may stand in one place in front of the machine throughout the lasting process on each shoe; 50 the shoe being easily accessible in its pulling and wiping positions, and the various controlling, adjusting and operating levers, wheels and the like being easily reached by hand or foot. The main frame or base 37 55 of the machine is shown as provided with an upstanding bracket 38, which supports the jack and pulling-over mechanism, similarly, in a general way, to my prior Patent No. 1,260,034. At the left and right ends 60 of the base are extensions 39 and 40, above which are supported the heel and toe wiping mechanisms respectively. The general location of the shoe holding jack 43 is between the heel and toe wiping heads 45 65 and 46, beneath and forward of the gripper

devices of the pulling-over mechanism 42; its shoe clamping portion swinging from in front of the grippers forwardly and downwardly to a position between the wiping mechanisms, as indicated in the figures. 70

The initial or pulling position of the shoe is as shown in Figs. 1, 3, 4 and 7, with its toe end pointing upwardly and the sole or bottom of the last facing rearwardly, from the operator. The initial location of the 75 shoe is higher than its final or wiping location, so that as permitted by the illustrated jack, the shifting of the shoe brings it from the higher to the lower level, thus giving the greatest convenience to the operator in both the pulling and the wiping operations. Figs. 17, 19 and 20 show the intermediate position of the shoe and jack, they having swung downwardly and forwardly. The next shift is a swinging to 80 the right of the shoe heel, so that the shoe and clamp take the final or wiping position shown in Fig. 18. The shoe is here inverted, and the forepart of the last is substantially horizontal, with the toe end at 85 the left and the heel end at the right in proper relations to the toe and heel wiping mechanisms 46 and 45. While the shoe rests in the intermediate position of Fig. 17, the operator may if desired perform the 90 so-called side lasting operations, which are usually hand operations readily performed at this stage of the lasting process.

Before describing the full operation and structure of the different mechanisms, pulling, jack and wiping, I will state the following novel features of inter-relation. In the use of the machine herein illustrated the shoe initially is positioned by the operator with reference to the position of the pulling-over grippers. As shown in Fig. 3, the shoe is brought up to the toe gripper and set between the side grippers. The shoe at this time is held against the shoe rest or abutment, which is between the gripping mechanisms, and it is not yet engaged by the jack clamp, as shown in Fig. 3. In the prior patent the shoe was set to a given height with respect to the jack clamp, and the gripping mechanism was bodily adjusted vertically to the shoe. The present machine is an improvement in that the pulling mechanism requires no vertical adjustment for different lengths of shoe, the shoe being set to the mechanism as just described. When the pulling has been completed, the jack, which meanwhile has remained in its lowered or wiping position, is swung up and the toe pad of the jack clamp comes into position at a predetermined height against the top of the 110 shoe toe. The position or height of the toe pad is initially set in accordance with the pulling-over mechanism. The heel-end of the shoe is required to be supported, and the jack comprises a heel spindle adapted to 115

120

125

130

enter and engage the last within the shoe. This in the present machine is adjustable longitudinally in the jack, that is, vertically when applying the jack to the pulled-over shoe. When the toe clamp and the heel spindle have been set and the shoe secured, the pullers may release the shoe, and the jack and shoe may be swung down frontward through 90°, the toe pointing front as 5 in Fig. 17. Another feature is that the subsequent swinging of the shoe to set it to the wiping mechanisms is a swinging about an axis substantially at the middle of the toe 10 end of the shoe, as will be clear in Figs. 18 and 22. In other words, the shoe heel and the heel spindle are to be swung around from the rear to the right, so that the shoe 15 shifts from the Fig. 17 to the Fig. 18 position when it is in readiness for the wiping 20 operations.

At the front of the machine are shown three pedals, 48, 49 and 50, each having a spring normally lifting it. Pedal 48, after the lasting of a shoe is completed, serves to 25 wholly release the shoe from the jack and restore the latter to condition ready to be elevated to receive the next shoe from the pulling-over mechanism.

The central pedal 49 is for applying by 30 foot the pulling force, it simultaneously operating the pulling grippers at the sides and end of the shoe toe. This pedal when depressed is locked in place, and the right 35 pedal 50 serves the purpose of unlocking the main pedal when the pulling is finished.

Before describing the pulling connections from the main pedal the locking of the latter may be conveniently explained. Fig. 3 shows that the pedal 49 is fulcrumed at the 40 far rear at 51. About one-third of its length from this point extend the connections to the pullers. About one-third of its length from the front is the following locking mechanism. A serrated rod 52 is fulcrumed to the pedal and extends upwardly 45 to a point within a barrel 53, seen also in Fig. 2. At the top of the rod 52 is a head 54 sliding vertically in the barrel, and between the head and the bottom of the barrel 50 is a compressed spring 55. The barrel is substantially fixed, but a slight swinging is 55 permitted to adapt it to the movements of the pedal, by reason of a fulcrum 56, connecting the top of the barrel to a projection 60 on the base 37 of the machine. When the pedal is depressed, the descending head 54 compresses the spring 55, which tends to react on release of the pedal to restore it to its raised position. It will be understood 65 that the pedal will be depressed to varying extents with different shoes, the shoes being pulled over under observation. It is desirable to lock the pedal in its lowermost position, and this is effected through the teeth ar- 65 ranged along the length of the rod 52. Near

the bottom of the barrel 53 is a pawl 57 sliding horizontally in a fixed guide. A centrally pivoted lever 58 is connected to the pawl below, while at its upper end a spring 59 presses to the right, so that the pawl has 70 a tendency to engage the teeth of the rod 52. To whatever point the pedal is depressed, it will be held down by the rod and pawl. It will be understood that after this operation the perfecting of the pulling operation is performed by the separate individual levers at the top of the machine. When the pulling-over is completed, and the jack has been engaged with the shoe, it is necessary to release the pulling mechanism 75 and permit the opening of the grippers thereof. The pedal 50 serves this purpose. When depressed it acts through pedal rod 60 to swing a bell crank lever 61, shown in Fig. 1, the free extremity of this pressing left- 80 wardly against the upper end of the lever 58. By this the depression of the puller unlocking pedal 50 removes the pawl 57 from the toothed rod 52, permitting the spring 55 to assert itself and restore the 85 main pedal 49 to its upper position.

When the pulling pedal 49 is depressed, this serves to close and pull rearwardly all of the pulling grippers, of which three are shown, one at the extreme toe, and one at 90 each of the two sides of the shoe in proximity to the toe; and these will be termed the toe gripper 64, the left side gripper 65 and the right side gripper 66, respectively. It will be convenient to describe the construction and action of the grippers in respect to 95 their closing and opening, and their pulling and return movements, before describing the connections from the pedal 49. During the pulling the shoe, or rather the insole beneath the wooden last, bears against a system of abutments, three being shown, these herein associated respectively with the three grippers, namely, the toe abutment 68, the left side abutment 69 and the right side 100 abutment 70.

The toe gripper 64 consists, as seen in Fig. 4 of a forwardly and rearwardly sliding shank 72, engaged in a rear bearing 73 and a front bearing 74, while a spring 115 75 between bearing 73 and a collar on the shank tends to press forwardly the gripper. The spring acting to throw the shank forwardly shifts forward and opens the gripper, this action being limited by the 120 contact of the collar with the bearing 74. The gripper itself is at the forward end of the shank 72, and consists of a front jaw 76, mounted on the shank, and a rear jaw 77 pivoted to the shank and having its upward 125 extension pivoted to a longitudinal bar 78, which may be termed the tail of the gripper, it serving when pulled rearwardly to swing the rear jaw, and thereby close the gripper. The gripper closing tail 78 is 130

formed with a hook or notch at 79, engaging on a lug or block 80, loosely surrounding the gripper shank 72 and having lateral pins 81 by which the block may be shifted longitudinally of the shank.

It will be obvious that, if the block 80 is forced rearwardly while engaged by the hook 79, this will first effect the closing of the gripper upon the upper of the shoe, and 10 its continued rear motion will, against the resistance of spring 75, retract the entire toe gripper, thus giving the desired pulling action.

It will be convenient at this point to explain 15 the pedal connections for this purpose. Referring to Fig. 4 in connection with Figs. 3 and 9, an upright connecting rod 84 is shown extending from the pedal lever 49 to a bell crank 85, by which the downward 20 pedal pull is converted into a forward motion of three parallel rods 86, each serving as a connection between the bell crank 85 and a lever 87, of which there are three, as seen in Fig. 9, fulcrumed at a higher point 88. A 25 strong but adjustable spring 89 is interposed between each rod 86 and lever 87 in order to limit the total pulling pressure upon the leather, which without a resilient connection might be unduly stretched and injured by 30 the pedal action.

The three levers 87 at their upper ends have three separate upward extensions, 91 in the center, 92 at the left and 93 at the right, respectively, for communicating the 35 pulling force to the three grippers, respectively. Inasmuch as the grippers are shiftable for right and left shoes, or for adjustment, or both, the lever extensions 91, 92 and 93 are rendered adjustable or adaptable 40 thereto by their being fulcrumed at 94 to the levers 87, respectively. The extension 91 for the central or toe gripper is formed with a yoke 95 surrounding the block 80, before mentioned, and engaging the pins 81 thereof, 45 so that the rearward movement of the lever pulls rearwardly on the block to close and pull the gripper, as described. Fig. 9 shows that the extensions 92 and 93 have similar yokes 95, performing analogous functions 50 for the left and right side grippers. The toe gripper lever has an upwardly extending handle 96, by which the gripper can be additionally manipulated after the pedal operation is completed and the pedal locked 55 downward. Similar handles 97 and 98 for the left and right sides grippers are provided, but not directly on the lever extensions 92 and 93, but through hubs 99 extending from the transmitting levers to the handle levers, as shown in Fig. 9.

Each of the three grippers, in addition to the adjustments to the described, is capable of a bodily shifting or swinging motion adapting it alternately to right and left 65 shoes. The nature and extent of the adjust-

ment of each is dissimilar, and they are, therefore, separately mounted and fitted for this purpose. The toe gripper has the greatest amount of shift for reversing the machine, and this motion and the fittings will 70 be described before describing the side grippers and their movements.

The toe gripper is carried bodily on a composite frame, which is mounted to swing about a point approximately at the ball of 75 the shoe. Fig. 7 shows the gripper set for a right shoe, and Fig. 8 shows the same reversed for a left shoe. The reversing motion is about a center or axis determined by the fulcrum rod or axle 101, supported in a 80 stationary head 102. At the front end of the axle are the following. Extending upwardly from it is a rod 104, on which slides a sleeve 105, carrying the toe abutment 68 before mentioned. A spring 106 presses the sleeve 85 and abutment upwardly against a stop or pin 107, mounted at the underside of the forwardly extending part of the bearing 74 of the toe gripper shank before mentioned. By this arrangement the toe abutment 90 always takes its correct position both vertically and laterally. Extending downwardly from the axle 101 is a bar 103, having at its lower end a switch cam device, whereby the pulling-over mechanism is automatically reversed after operations on each shoe, as later described.

The axle 101 of the toe gripper system extends through the head 102, and at rearward points is provided with the following. An 100 upwardly extending bracket 109 affords a fulcrum 110, about which the entire toe gripper with its slide bearings 73 and 74 may be tilted or vertically swung. As seen in Fig. 4, the bearings 73 and 74 are rigidly 105 connected, forming a sort of frame, and by lifting the rear end of this frame the toe gripper can be slightly lowered to bring it into correct relations with the side grippers. This initial adjustment may be effected by 110 an adjusting device 111, comprising right and left threaded rods entering a threaded wheel, which can be turned to raise or lower the rear bearing 73, thus swinging the frame and tilting the gripper, as stated. It will 115 be noted that the yoke 95, see Fig. 3, is slotted to permit the pins 81 on the block at the rear end of the gripper shank to be vertically adjusted. The entire described system also may swing to right or left, the actuating 120 lever 91 being fulcrumed, as already explained, to permit its swinging to accommodate this reversing action.

When the described toe gripper system is swung from right to left or vice versa, 125 the extreme positions are determined by stop devices, shown in Fig. 7. On the stationary head 102 is slidingly arranged a left stop 113 and a right stop 114. Engaging in both of these is a right and left screw 115, 130

having at its central part a positioning collar 116, held against longitudinal play. At its right extremity the threaded rod has a thumb nut 117, which may be turned to 5 symmetrically separate or draw together the stops 113, 114, so that they may be set to suit the shoe being lasted.

I prefer that the described mechanism be automatically reversed after the lasting of each shoe. To assist this purpose a device 10 may be employed for automatically restoring the downwardly extending bar 103 to a vertical or central position whenever it is free. Such a device is indicated conventionally by the opposite springs 119. At 15 the foot of this bar, as before stated, is a switch cam device taking part in the reversing operation. This is seen in Fig. 7, and in plan view or diagram in Fig. 10. The 20 switch cam is centrally pivoted at the foot of the bar, and has a wedge portion 120 directed rearwardly, and at each side the cam or reversing portions 121, 122. This 25 device co-operates with a sliding cam 124, shown also in Fig. 4, mounted to slide forwardly and rearwardly within the open portion of the upwardly extending bracket 38 of the machine. The forward end of this 30 cam or wedge is pointed, and is directed toward the pivot of the switch cam 120. The sliding cam has invariably a straight forward and rearward movement, being normally pulled rearwardly by a spring 125. But the switch cam is centrally pivoted and 35 capable of a slight oscillation so that its wedge or point 120 may pass to either one or the other side of the point of the sliding cam. The stop pins indicated in Fig. 10 limit the swing of the switch cam. In this 40 figure the wedge 120 is indicated as slightly to the right, rather than to the left, of the point of the sliding cam. The sliding cam is pushed forward at each down-swinging movement of the jack, namely, by means of 45 a lug 126, adapted to be struck by the counterweight of the jack as the latter comes up and forward into position. It will be understood that the counterweight remains in the position indicated in Fig. 4 through- 50 out the pulling-over operation, and only recedes when the jack is swung upwardly to receive the pulled-over shoe. With the parts normally in the position shown in Fig. 55 10, the machine just having pulled-over a left shoe, the sliding cam, as it comes forward with the descent of the jack, engages at the left side of the wedge 120, and this bodily thrusts the switch cam and the carrying bar 103 toward the right. This 60 continues now until the parts come to the dotted line position which is shown, and here the pullers stand reversed for the right shoe. It will be noticed that in going through this 65 action the switch cam itself is reversed. Its wedge 120, as shown in dotted lines, is

swung over to the left of its central position. When the bar 103 is subsequently centered, after the next pulling-over operation, the succeeding forward movement of the sliding cam will catch on the right side of the switch 70 cam, and thus throw the bar 103 to the left, thus setting the machine for a left shoe. When the cam 124 recedes the bar 103 remains in its extreme position at one side because at this time the shoe is in pressing 75 contact against the toe abutment 68. To allow for adjustments and prevent breakage, the switch cam is rendered able to yield at the end of its throw by reason of a pair of strong springs 127 at the foot of the bar 80 103 yieldingly holding the switch cam device to its illustrated position, the switch cam being mounted to slightly swing or rock about a horizontal axis for this purpose.

It has been explained how the toe abutment 68 follows the toe gripper not only in its swinging, but in its up and down adjustment. The side abutments 69 and 70 are herein correspondingly shifted, so that during the wiping operation on any shoe the 85 abutments will be spaced at proper distances, and near the periphery of the shoe. Thus, in the plan view Fig. 11, the left side abutment 69 is shown as movable outwardly and inwardly by reason of being carried upon 90 a swinging arm 129, pivoted at 130, and spring pressed outwardly, so that the corner of the lever will bear against the left side gripper 65, thus bringing the abutment to the proper position.

The side grippers are of a special form, as seen in Figs. 11, 12 and 13, and elsewhere. The front or outer jaw 131 is almost hook-shaped, reaching around in front of the rear or inner jaw 132, the nose of which is sufficiently rounded to prevent injury to the upper U. The two jaws are mounted on a carrier 133, the outer jaw pivoted to move relatively from and to the other, and an equalizing provision is made for the carrier, 105 as seen in Fig. 12, this consisting in parallel links 134, extending from the upper and lower parts of the carrier to a centrally pivoted lever 135, connected to the rearwardly extending guide shank 136 corresponding to the shank 72 of the toe gripper. Between the members 135 and 136 are the 110 following.

In order to hold the side gripper approximately in its operative positions without 115 interfering with its rocking or equalizing action, the link 134 is provided with an extension 137, as shown in Fig. 12, bearing upwardly against an adjustable stop 138. This prevents the side gripper dropping from its 120 illustrated position. A yielding pin 139 bears upwardly against the extension 137 in opposition to the stop pin. The gripper is thus kept approximately at the correct vertical height, with a possibility of its lifting 130

somewhat in the pulling action, and with perfect equalizing freedom. The members 138 and 139 are both mounted on an enlargement or head 136^a at the forward end of the gripper shank 136. In order that the gripper will not accidentally become rocked away from its illustrated normal position, the pivoted lever 135 is provided with an extension 140 bearing forwardly against an 10 adjustable stop 141 and yieldingly pressed thereto by a spring pin 142, the two last mentioned parts being mounted on the head 136^a. The equalizing or rocking action is always one in which the lower edge of the 15 side gripper retracts further than the upper edge, which latter is at the cap portion of the upper and less apt to yield. The device 141, 142, therefore, permits the yielding that occurs in practice, while serving to normally restore the parts to the position shown in Fig. 12.

The side grippers are not only carried by the shanks 136, which guide them in their retracting and return movement, but they 20 adjustably swing about these as fulcra in reversing the machine for right or left shoes. Thus, as shown in Figs. 7 and 13, the side grippers are placed for a right shoe, and in Fig. 8 for a left shoe. Each of the axles 25 or shanks 136 is mounted in a pair of bearings 143, front and rear, upstanding from a carriage 144, and these two carriages, as seen in Fig. 4, have a dovetailed connection to the rear side of the stationary head 102. 30 This is for the purpose of symmetrical adjustment of the carriages from and toward each other, which may be effected by a right and left screw 145, engaging in oppositely threaded lugs 146, and having a thumb nut 147 for effecting the adjustment for variations in widths of shoes.

The swinging of the side grippers for right and left shoes may be effected and controlled as follows. On the reversing axle 45 101 of the toe gripper is mounted an arm 149, as seen in Fig. 16, and arms 150 on the side gripper axles 136 are shown as connected to each other by right and left threaded rod 154, turned by adjusting nut 155. 50 Springs 151 connect the arm 150 with the central arm, so that, when the toe gripper is reversed, the spring at one side will pull and cause both side grippers to shift, for example, into the position shown in Figs. 7, 55 13 and 16. Its extent of shifting is limited by the co-acting stops 152 and 153, shown in Fig. 13. The side grippers are thus adjusted in conformity to the shoe at the same time that the toe gripper is shifted across from the Fig. 7 to the Fig. 8 position.

The side gripper shanks 136, like that of the toe gripper, are provided with springs 60 161, pressing forwardly on collars so as normally to hold the side grippers forward and open. Also riding loosely at the rear end of

each shank is a block 162, having pins 163, engaged by the yokes 95 through which the pulling-over pedal causes the rearward pulling motions. The shank 136 is merely a guide, and the actual pulling is performed 70 by the side gripper tail 164, which, as seen in Figs. 4, 11 and 12, extends forwardly from the block 162 to the gripper. The tail is arranged to first close the gripper as it starts pulling rearwardly. The front 75 or outer gripper jaw 131 normally stands wide open, it being pivoted on the carrier 133. The hub of the jaw is provided with a few teeth, engaging corresponding teeth in the hub of a lever 165, extending outwardly and directly connected to the gripper tail 164.

By this arrangement, when the pedal is depressed, the rearward pull on the tail 164 first closes the gripper, as seen in Fig. 11, 85 and the continued movement bodily retracts the gripper, giving the desired pulling action.

Assuming now that the main pedal 49 is lifted and the three grippers are forward 90 and open, the operator places the shoe approximately as shown in Fig. 4, setting the skirts of the upper within the jaws of the grippers. The width separating the side grippers and the height of the toe gripper 95 will have been previously adjusted to the style and size of shoe, and other initial adjustments made, after which only the following operations need take place. There is no bodily vertical adjustment of the pulling-over mechanism, according to the length of the shoe, but, on the contrary, whatever its length, the shoe is set to the grippers. It is placed with the insole bearing against the three abutments, and the upper within 105 the jaws. By now depressing the main pedal, the three pairs of jaws are first closed and then retracted, giving the desired pulling action. The equalization of the side grippers prevents unequal pulling. When 110 the pedal has been sufficiently depressed, the foot may be removed and the pedal holds its position. The operator may then manipulate the three pulling handles 96, 97 and 98 to give exactly the pulling effects desired. 115 The jack to be described will now be swung up to the shoe, the heel spindle lifted more or less to engage the socket in the last, and the shoe firmly clasped and clamped within the jack. A touch on the pedal 50 now 120 releases the main pedal, thus letting all the grippers move forward and open and release the shoe. The jack will then be swung down and the shoe shifted to wiping position, as will be described. The swinging down of the jack brings its counter-weight up and forward so as to act on the reversing cam shown in Fig. 10, so that it will automatically throw the three grippers across to their opposite position, mak- 125 130

ing them ready for the other shoe of the pair. After the wiping and before the jack is lifted, the other shoe of the pair is placed in relation to the grippers, and 5 operations repeated.

Coming now to the shoe holding jack, this is shown in its swung-up position in Figs. 1 and 3, and in its swung-down or intermediate position in Figs. 17, 19, 20, 10 22 and 23, and in its final or wiping position in Fig. 18. The jack mechanism is supported at the free end of a swinging arm 170, fulcrumed at 171 on the upright bracket 38 of the machine. Between the 15 two sides of the bracket is located a counter-weight 172, of such form and weight as to substantially balance the jack, thus facilitating its manual lifting and dropping. At the free end of the jack arm 170 it is enlarged or formed into a head 173, affording support to practically all of the shoe clamping mechanism of the jack. In order to position the jack in its swung-down position, the bracket 38 of the machine is 20 formed with a forward extension or web 174, supporting an abutment or contacting piece 175, which is engaged by shoulder 176, formed at the left side of the free end of the jack arm 170. At this point might 25 also be mentioned the hooked member 177, mounted on the jack, adapted to be swung when the shoe is swung, so as to engage in the slot or recess at the upper side of a boss 178, upstanding from the frame of the 30 machine, to position and steady the shoe against longitudinal motion.

Supported in the head 173 of the jack arm is the rotary support 180, this extending forwardly horizontally when the jack 40 is in up-swung position, and extending downwardly beneath the head 173 when the jack is in wiping position. The rotary support is held in the head by a suitable flange beneath the head 173 when the jack is in 45 wiping position. The rotary support is held in the head by a suitable flange and collar. At its extremity the rotary support 180 rigidly carries a laterally extending arm or frame 181, which is secured by key 182 to 50 the rotary support 180. The rotary support carries the toe engaging devices or pads, while the swinging frame 181 carries the underreaching claw devices that engage the shoe sole, and also the heel engaging 55 spindle. It will be understood that this whole shoe engaging or clamping system is bodily swingable in the head 173 of the jack arm, the rotary support 180 forming its axis. I prefer that the shoe clamping 60 system shall be freely swingable in the jack arm head, and, as shown in Fig. 3, this enables the operator to readily adjust the jack to the shoe which has been pulled over, while, as seen in Figs. 17 and 18, the clamping devices and shoe are enabled readily to

be swung to bring the shoe into correct wiping position. In these figures the hooked arm 177 before mentioned is shown as mounted at the lower extremity of the rotary support 180, so that, when the shoe 70 is swung into wiping position, the hook 177 engages in the fixed groove of member 178, thus anchoring and steadyng the jack and clamp mechanism against longitudinal displacements during the wiping operations. 75

The toe engaging devices are mounted on what may be termed the upper end of the rotary support 180, it being the upper end when the jack is in wiping position. These comprise a toe pad engaged generally at 184, 80 secured upon the head or block 185, the shank 186 of which extends concentrically within the recessed interior of the support 180. The shank and the support are keyed together by a key 187, so that all of the shoe 85 engaging parts will swing together as a single system. An adjusting screw 188 enables initial adjustment of the relative position of the toe engaging pad to allow for shoes of different thicknesses. 90

The details of the toe engaging pad 184 are shown in Fig. 24 in connection with Figs. 19, 20 and 22. An equalizing or rocking lever 190 is pivoted directly to the block 185, and the extremities of this lever carry 95 a pair of bent levers 191, each of which carries an inner clamp block 192 and an outer clamp block 193, so that we have a system of four self-adjusting clamping blocks bearing against the rear face of the 100 leather or other flexible toe clamping pad member 194. To render the toe clamping device absolutely universal, each of the four blocks 192, 192, 193, 193, is pivoted to its carrying lever. Thus, the two inner blocks 105 192 have their shanks extending loosely into recesses in the levers 191, with transverse pivot pins 195 giving the necessary play longitudinally of the shoe. The outer clamp blocks 193, on the contrary, are sufficiently 110 taken care of by swinging about their own pivot shanks 196, each of which is retained in the recess in lever 191 by a retaining pin 197.

The heel engaging devices are carried by 115 a sliding carriage 200, well shown in Figs. 20, 22 and 23, this having depending side flanges 201 and a dovetail connection 202 with the top side of the swinging frame 181. The heel spindle carriage 200 is formed with 120 a sleeve or barrel 203 to contain the spindle. It will be understood that the carriage is slid along the frame until in proper position for the spindle to engage the heel end of the last, and when set it may be locked in 125 place by a device 205.

The heel spindle 207 is slidingly fitted within the sleeve or barrel 203. A flange 208 at the top of the spindle prevents it from dropping out of the sleeve. The spin- 130

dle is provided with a head 209 at the lower end, by which it conveniently may be thrust into shoe engaging position. A spring 210 between the head 209 and the sleeve tends to 5 retract the spindle from the shoe. In order to lock the spindle into engagement with the last, it is formed with teeth or serrations 211, engaged by a pawl 212, the tail 213 of which is formed with an inclined or cam 10 surface to co-operate in retracting the pawl, which is spring pressed, toward the teeth of the spindle. For swinging the pawl to unlock the spindle after the completion of a shoe, a sliding rod 214 is provided, mounted in the carriage 200, and, as will be later described, this unlocking rod is adapted to be 15 lifted by the depression of the pedal 48 after the wiping of a shoe.

After the toe pad 184 and the heel spindle 207 have been engaged with the shoe, a 20 pair of claws or hooks 217 are brought into action against the sole of the shoe to press the shoe forcibly in position to the toe pad and heel spindle, and thereby rigidly clamp 25 the shoe in the jack. When the jack is swung up to the Fig. 3 position in readiness to engage the shoe after the pulling-over, the claws 217 extend substantially as 30 shown in Fig. 3 in readiness to be swung together and pulled forwardly as stated. The fittings and operating devices for the claws will now be described.

Each claw is mounted on a pivoted shank 218, these shanks being pivoted to a sliding 35 sleeve 219, which surrounds the rotary support 180 and gives guidance to the claws in their forward and rearward movement. In Figs. 19, 20 and 22, the sleeve and claws are shown in their retracted or forwardly drawn 40 position. Normally they will be in the opposite position. The guide sleeve 219 has lateral ears 220 to which the shanks 218 of the claws are pivoted, and from the pivot 45 the shanks are bent or formed with feet 221, extending toward each other so as to both operatively engage an actuating member 222, which by its relative movements is capable of thrusting the claws apart or together.

The member 222, which is connected to the 50 claw shanks, is provided with a sliding shank 223, having an enlargement 224 at one point, engaging slidably in a barrel 225, secured rigidly to the swinging frame 181. Surrounding the shank 223 and confined between the enlargement 224 and the head of 55 the barrel 225 is a spring 226 tending always to thrust the member 222 toward the shoe, and thereby separate the claws, a cross spring 227 controlling the claws against excessive swinging apart.

In Fig. 23 in dotted lines is shown the 60 normal position of the claws 217, that is, before they have been applied to clamp the shoe in the jack. It will be obvious that, if 65 the shank 223 be forcibly pulled from the

shoe, this will act, first, to throw the claws toward each other, the continued movement pulling the claws bodily, as guided by the sleeve 219, until the same are brought into the shoe engaging position shown in full lines in the figures. Preferably, in order to obviate the claw shanks contacting the sides of the shoe uppers, a pair of adjustable stops 229 are provided on ears 230, extending from the guiding sleeve 219, these stops being 70 so positioned that, as the retracting action takes place, the feet 221 of the claw shanks engage the stops as the claws reach the desired degree of approach. This contact is followed by the bodily retraction of the entire claw system. 75

In order to facilitate the convenient and effective operation of the shoe engaging claws, the following construction may be adopted. The shank 223 of the claw swinging and retracting member 222 is extended through the head of the barrel 225, and at its extremity provided with collars 233. The shank and the collars engage with the U-shaped depending portion 234 of a sliding 80 and rotating sleeve 235, the body of which surrounds the barrel 225. When the sleeve 235 is moved toward or from the shoe, this carries with it the shank 223 and the remainder of the claw operating parts. In 85 order to effect this operation, the following operating mechanism may be employed. The barrel 225 is exteriorly threaded, as shown at 238. The external sleeve 235, which slides and rotates outside of the barrel, is provided with an outstanding lug 239, between which is fulcrumed a lever 240, extending outwardly to a point of convenient access, and formed at its inner extremity as a curved 90 rack or gear 241. The teeth on the operating lever 240 engage in the threads surrounding the barrel 225. The gear and screw co-operate in two respects, first, in the manner of a rack and gear to give an extended movement to the sleeve and connected 95 parts, and thereafter as a screw and nut, to give a further and more forcible action. Thus, when it is desired to apply and forcibly 100 clamp the claws against the shoe bottom, the handle 240 will be pulled from the shoe. The engagement of the teeth 241 with the screw 238 causes the sleeve 235 and connected parts to retract, so that, as before described, the claws 217, which swing together, are 105 drawn forcibly against the shoe. At this stage I prefer to lock the lever 240 so as to hold the adjustment. For this purpose, as shown in Figs. 19 and 20, I provide a lock 110 lever 243 adjustably connected to the operating lever 240. The locking lever is fulcrumed on the pivot of lever 240, and its extremity is slotted to receive a pin 244, adjustably mounted on the lever 240 by means of a sliding block 245, adjustably shiftable 115 by threaded screw 246. The opposite end 120

125 of the lever 243 is adjustably connected to the operating lever 240. The locking lever is fulcrumed on the pivot of lever 240, and its extremity is slotted to receive a pin 244, adjustably mounted on the lever 240 by means of a sliding block 245, adjustably shiftable 130 by threaded screw 246. The opposite end 135

247 of the lever 243 is adapted to engage with the notch or shoulder 248 of a latch lever 249, mounted on the sleeve 235 and brought into locking position either by hand 5 or by spring if desired.

The described mechanism gives a quick and ready means of bringing the claws 217 into pressing engagement with the shoe; but, as a quite forcible pressure is desired, greater 10 than can be obtained by a device of this sort, I now utilize the screw threads 225 in conjunction with the teeth 241 for the purpose of giving a further pull and additional pressure. To accomplish this it is only necessary, after the handle 240 has been pulled 15 from the shoe and there locked, to throw the handle around counterclockwise, thereby rotating the sleeve 235 and all the parts carried by it, the teeth 241 during this action 20 engaging and traveling around the screw threads 225, thus further retracting the entire claw system to any desired extent. During this action it will be understood that the spindle 223 of the claw retracting member 222 is prevented from rotation by the confining of the member 222 between the sleeve 219 and an overlying plate 250.

The tail of the latch lever 249, which in Fig. 19 is shown extending horizontally to the left, and which in wiping position will extend horizontally to the rear, is adapted to be contacted and lifted when the pedal 48, previously mentioned, is depressed after the completion of a shoe.

I have herein provided means for engaging and retaining against the last of the shoe the freshly pulled-over edge portions of the upper. Thus, in Figs. 3, 19, 20 and 22 are shown a pair of opposite retaining 35 members 253. These will be seen in Fig. 3 to be adjacent the side pulling grippers so as to be effective in acting upon the freshly pulled leather at those points. Instead of having the retainers merely press laterally, 40 as indicated in the figures mentioned, they may be somewhat extended and curved around, as in Fig. 25, so as to actually underreach the shoe sole and more securely retain the pulled upper in position. The retainer in this case may be applied before 45 the puller has released the work and retracted, and as soon as the work is released the retainer 253, not taking the position shown in Fig. 25, may first effect a smoothing or wiping action of the leather; afterwards holding it in the position shown.

In either form the retainers 253 are preferably mounted on resilient shanks 254, which in turn are mounted on swinging carrier blocks 255, pivoted upon ears 256 on the head 285 of the toe clamping pad. The general plan is to swing the carriers 255, and thereby place the spring shanks under stress, so that in the modification shown in Fig. 25, 60 the wiping and retaining action described

will actually take place by reason of the pressure and motion of the spring.

In order to swing the blocks 255, each is provided with a series of teeth 257 facing each other, and between these runs a double rack 258, the shank 259 of which extends axially through the shank 186 of the toe clamp pad head, and thence forwardly and axially through the rotary support 180, to where at its forward end the shank 259 70 of the double rack is provided with a notch or hook by which it may be actuated. Through a slot 260 formed in the rotary support 180 extends a finger or elongated tooth 261, adapted to engage in the notch 75 in the sliding shank 259, as best shown in Figs. 19 and 20. The finger is normally in its inward position, but may be moved outwardly by an unlocking lever 262, pivoted exteriorly to the sleeve 219, and acted upon 80 by a spring 263, which tends to thrust the finger inwardly.

The action of the described retainer mechanism is as follows. When the lever or handle 240 is pulled forwardly to apply the claws 217 to the shoe sole, this, as previously explained, causes the sleeve 219 to slide forwardly. Through the engagement of the finger 261 with the sliding shank 259, the latter and the rack 258 are drawn forwardly, 90 and the retainers 253 are thrust toward each other and against the upper of the shoe, as already stated.

The connections from the unlocking pedal 48 may now be described. Extending upwardly from the pedal 48 is a rod 267, which, as will be clear from Figs. 1 and 3, is pulled down by the depression of the pedal. This swings downwardly the rear end of a lever 268, causing the front end to 100 rise, and thereby to lift the slide 269, having a horizontal arm 270 at its top. This unlocking arm 270 extends directly beneath the members which effect the unlocking of the lever 240 by which the shoe engaging 105 claws are applied, and the pawl 212 by which the heel spindle is unlocked. The relation of the parts is shown in Fig. 19, where the unlocking arm 270 is shown to be in position beneath the tail of the latch lever 249 110 and the bottom of the pin 214, through which the pawl 212 engages.

It will thus be seen that I have described a shoe lasting machine including the pulling over mechanism, also a shoe holding and shifting means or jack, also wiping mechanisms, the same embodying the principles and attaining the advantages of the present invention. Since many matters of combination, arrangement, design, procedure, structure, and detail may be variously modified without departing from the novel principles involved, it is not intended to limit the invention to such matters except in so far as set forth in the appended claims.

What is claimed is:

1. In a lasting machine, a plurality of pulling grippers relatively adjustable for different shoes, a plurality of separate sole abutments independent of the grippers but also adjustable for shoes of different size or shape and adapted to be directly contacted by the shoe sole and give support thereto during the pulling operations, and means operative to shift the said abutments to proper positions by the adjustment of the grippers.
2. Lasting machine as in claim 1 and wherein there is a toe apex gripper, and a side gripper at each side, with an abutment adjacent the toe and one near each side, each abutment connected to shift with its adjacent gripper during adjustment or renewal of gripper position.
3. In a lasting machine, pullers, a pulling pedal for closing and retracting the pullers, a lock device for holding the pedal in position when pulling a shoe, consisting of a serrated shank (52) attached to the pedal and slideable in a guide, and a movable engaging piece (57), and means for at will separating the members of the lock device to release the pulled shoe.
4. In a lasting machine, a side gripper, an operating lever or pedal, and connections therefrom to the gripper including equalizing means, said equalizing means consisting of links on which the gripper floats, permitting rocking movements and also up and down movements, whereby the gripper adjusts itself to the resistance of the work during pulling.
5. In a lasting machine, a side gripper, an operating lever or pedal, and connections therefrom to the gripper including equalizing means, so constructed and arranged that the gripper is yieldingly held in normal position but capable of rocking and also moving up and down, whereby the gripper adjusts itself to the resistance of the work during pulling.
6. In a lasting machine, a gripper, a gripper carrier, as 136, 136^a, a retracting rod separate from the carrier, said rod so arranged and connected with the gripper that upon its retraction it first closes and then retracts the gripper, and floating connections between the carrier and gripper.
7. In a lasting machine, a gripper, a gripper carrier (136, 136^a), means for closing the gripper and retracting the carrier and gripper, and floating connections between the carrier and gripper, comprising a rocker mounted on the carrier, links from the rocker ends to the gripper ends, and yielding means holding the rocker and gripper in normal position.
8. In a lasting machine, a gripper, a gripper carrier (136, 136^a), means for closing the gripper and retracting the carrier and gripper, and floating connections between the carrier and gripper, comprising a rocker mounted on the carrier, links from the rocker ends to the gripper ends, a spring permitting the lower end of rocker and gripper to retract relatively more than the upper, and a rigid stop opposed to said spring.
9. In a lasting machine a gripper, a gripper carrier (136, 136^a), means for closing the gripper and retracting the carrier and gripper, and floating connections between the carrier and gripper, comprising a rocker mounted on the carrier, links from the rocker ends to the gripper ends, a spring permitting the gripper to rise during pulling, and a rigid stop opposed to said spring.
10. In a lasting machine, a gripper, a gripper carrier (136, 136^a), means for closing the gripper and retracting the carrier and gripper, and floating connections between the carrier and gripper, comprising a rocker mounted on the carrier, links from the rocker ends to the gripper ends, yielding means to hold the rocker in normal position and other yielding means to hold the links in normal position.
11. In a lasting machine having pulling grippers at the sides of the shoe and a toe gripper, a toe gripper carrier, a front jaw secured thereon, a swinging rear jaw member arranged transversely of the front jaw and pivoted directly upon the front jaw, said member at one side of its pivot constituting the rear jaw and at the other side constituting an extension, a tail or pull rod connected to said extension, and means to pull said rod rearwardly to close the jaws and retract the gripper.
12. In a lasting machine a toe gripper and two side grippers, a swinging frame carrying the toe gripper at its top and adapted to swing symmetrically across to reverse the machine for right and left shoes, said frame comprising a laterally swinging bar at the front a carrier for the toe gripper, extending rearwardly from the upper part of said bar, and a swinging adjustable rod at the rear, adapted to alter the tilt of the toe gripper, and a toe abutment carried by said frame.
13. In a lasting machine a toe gripper and two side grippers, a swinging frame carrying the toe gripper at its top and adapted to swing symmetrically across to reverse the machine for right and left shoes, a shiftable carrier for holding right and left shoes alternately, and means whereby the shifting of the shoe carrier acts to reverse said frame after the lasting of each shoe.
14. In a lasting machine a toe gripper and two side grippers, a swinging frame carrying the toe gripper at its top and adapted to swing symmetrically across to reverse the machine for right and left shoes, a rock shaft carrying each side gripper, permitting it to

swing across for reversal, a rock shaft for the frame, said three shafts extending rearwardly, and means actuated by the swinging of said frame for automatically reversing the position of the two side grippers, consisting of rock arms on said three shafts and resilient connections between said rock arms.

15. In a lasting machine a shoe abutment, pulling mechanism for pulling over a shoe engaged on said abutment, a jack adapted to be shifted to the shoe after the pulling, having shoe engaging or clamping means bodily swingable on the jack about an axis near the toe end of the shoe.

16. In a lasting machine a shoe abutment, pulling mechanism for pulling over a shoe engaged on said abutment, a jack adapted to be shifted to the shoe after the pulling, having shoe engaging or clamping means bodily swingable on the jack about an axis near the toe end of the shoe, the jack being adapted to be swung front and down until the shoe toe points forward, whereby the clamping means and shoe may then be swung horizontally to bring the shoe to wiping position.

17. In a lasting machine pulling mechanism comprising grippers shiftable to reverse the machine for right and left shoes, a jack having shoe engaging means and shiftable from pulling to wiping position and return, and connections operated by the shifting of the jack for reversing the pulling mechanism.

18. Machine as in claim 17 and wherein the reversing connections comprise cooperating cam members on the jack and pulling mechanism, and a switch device automatically reversible on each operation.

19. In a lasting machine pulling mech-

anism, a jack adapted to engage each pulled shoe and then shift to wiping position, clamping means on the jack for holding the shoe during shifting and wiping, and means for unclamping the shoe after wiping.

20. Machine as in claim 19 and wherein the shoe engaging and clamping means comprises a toe engager and means for locking it to the shoe, a heel spindle and means for locking it to the shoe, and said unclamping means comprising a pedal or lever having connections for unlocking both said locking means.

21. In a lasting machine pulling over mechanism, a shiftable jack adapted to be engaged with the shoe after pulling, comprising a toe engaging pad, hold-down hooks, a device for applying said pad and hooks to clamp the shoe, and a member adapted to be engaged with and pressed upon the edge of the pulled leather to hold it during the shifting of the jack, and means for wiping the shoe while held in the shifted jack.

22. Machine as in claim 21 and wherein the leather holding member is a resilient finger.

23. Machine as in claim 21 and wherein the leather holding member is a resilient finger shiftable to and from the shoe edge.

24. Machine as in claim 21 and wherein the leather holding member is a resilient finger shiftable to and from the shoe edge, and having connections operated by the act of applying the pad and hooks for shifting it into pressing engagement upon the pulled leather.

In testimony whereof, I have affixed my signature hereto.

ANGELO PERRI.
